DESIGN FOR A TRANSPARENT PRISM VANITY LAMP

Edward L. Culwell, Alameda, Calif.

Application June 14, 1948, Serial No. 146,962

Term of patent 14 years

(Cl. D48—20)

To all whom it may concern:

Be it known that I, Edward L. Culwell, a citizen of the United States, residing at the city of Alameda, in the county of Alameda and State of California, have invented a new, original, and ornamental Design for a Transparent Prism Vanity Lamp, of which the following is a specification, reference being had to the accompanying drawing, forming a part thereof.

Referring to the drawing which shows by illustration my new design:

Fig. 1 is a perspective view of a transparent prism vanity lamp, showing my new design;

Fig. 2 is a front elevational view thereof;

Fig. 3 is a top plan view, and

Fig. 4 is a vertical transverse section.

I claim:

The ornamental design for a transparent prism vanity lamp, as shown,

EDWARD L. CULWELL.
